J. H. MEANS

STANDPIPE FOR COKE OVENS

Filed Dec. 2, 1920

WITNESS:

Gaston Henglinger.

INVENTOR:

John H. Means

BY

Francis J. Chambers
ATTORNEY

UNITED STATES PATENT OFFICE.

JOHN H. MEANS, OF MAYVILLE, WISCONSIN.

STANDPIPE FOR COKE OVENS.

Application filed December 2, 1920. Serial No. 427,689.

To all whom it may concern:

Be it known that I, JOHN H. MEANS, a citizen of the United States of America, and a resident of Mayville, in the county of Dodge, in the State of Wisconsin, have invented a certain new and useful Improvement in Standpipes for Coke Ovens, of which the following is a true and exact description, reference being had to the accompanying drawings, which form a part thereof.

My invention relates to coke ovens and particularly to the standpipes used in connection with the openings for the escape of gas formed in the tops of the ovens. As heretofore generally constructed and used the standpipes, usually of cast iron, have been supported above the openings in the tops of the ovens, a space between the standpipe and the oven top being sealed with sand. This construction has proved unsatisfactory because, owing to the high temperature of the gases, the base of the standpipe is apt to melt and the melted iron flowing into the ovens is very apt to damage them. Another draw-back found to exist in connection with this structure is that considerable and objectionable amounts of carbon are apt to be deposited in the standpipe. Again, the ordinary construction of standpipe is such that where a liquor stream or spray is used to wash and keep clean the valve and valve seat used between the standpipe and the collecting main, there is liability of some of the liquor flowing down the standpipe which is objectionable for many reasons.

The objection of my invention is to provide a standpipe structure which will be free from these defects and which will be highly efficient. In particular and generally speaking my invention consists in providing a water seal between the lower end of the standpipe and the gas escape opening in the oven for the double purpose of keeping the lower portion of the standpipe cool and of cooling the gases and of mixing with them vapor and water so that they will no longer deposit objectionable amounts of carbon in the standpipe.

Also, my invention consists in a construction by which the top of the standpipe is connected to the main or rather to a valve chamber opening into the main by a transverse downwardly inclined section or continuation of the standpipe.

My invention and its preferred construction will be best understood as described in connection with the drawings in which it is illustrated in which

A indicates the top of the oven structure, A' the opening from the oven through the top of the structure for the escape of gas. B is an ordinary supporting structure or frame for the collecting main indicated at C having an opening formed through its top as indicated at C' which connects with the valve chamber D having in it a valve seat D', a removable cover D², a door D³, a conduit extension D⁴ inclined upwardly from the valve chamber and a valve D⁵. E indicates the standpipe made up, as shown, of three cast iron sections E', E⁵, E⁶, the section E' having a downwardly inclined conduit extension E² which is bolted to the conduit extension D⁴, a lateral opening E³ for cleaning purposes and a cover E⁴. The lower extension E⁶ of the standpipe is formed with a downwardly extending flange E⁷ at its base and with an offset portion E⁸ and opening E⁹ for cleaning purposes. F is a water receptacle supported on the top of the oven structure and formed with a tubular passage F' extending through it which registers with the opening A' in the top of the oven. G is a water supply pipe and G' indicates an opening at the top of the water receptacle for maintaining the water level at a desired point. Any amount may be used for this purpose.

H is a standpipe extension or head formed with an inwardly extending flange H' at its top adapted to rest on the flange E⁷ of the standpipe the vertical depth of the extension H being such that when in position as shown in the drawing it will extend down below the water level in the water receptacle forming, as shown, a water seal. I is a spray pipe for liquor used to keep the valve seat and valve clean.

The water receptacle is preferably made of sheet metal, steel by preference, cast metal being less desirable for the reason that it is liable to crack and let the water run into the oven. The extension or head H is also preferably made of sheet metal, steel, while it is advisable to make the remaining portion of the standpipe of cast metal sections as shown.

In operation the hot gases from the oven issue through the opening A' and the tubular passage F' of the water receptacle to

pass through the head portion **H** into the standpipe and thence, the valve **D⁵** being opened, into the collecting main, the water in the receptacle keeps it and its tubular passage **F'** sufficiently cool while the heat effects a considerable vaporization of the water in the annular steam generator which mixes with the gases from the oven opening of course to somewhat cool them and preventing, as I have found, such deposits of carbon in the standpipe and its connections as were found to be troublesome in the older constructions.

The standpipe extension or head **H** is vertically movable so that it can be raised to clear the edges of the water receptacle and permit access to the water receptacle or permit it to be removed and replaced.

A liquor, preferably weak ammonia and tar mixed or either ammonia liquor or tar alone is preferably sprayed in through pipe **I** to keep the valve chamber its seal and valve clean and by inclining the conduit section **D⁴** and **E²** as shown **I** insure that the liquor will not flow into the standpipe.

Having now described my invention what I claim as new and desire to secure by Letters Patent, is:

1. In combination with a coke oven having an opening through its top for the escape of gas therefrom, a water receptacle supported on the top of the oven structure and surrounding said opening and a standpipe supported above the opening and extending into the water receptacle to a point below the water level therein.

2. In combination with a coke oven having an opening through its top for the escape of gas therefrom, a water receptacle supported on the top of the oven structure and surrounding said opening, a fixed standpipe supported above said opening and a vertically movable standpipe extension supported on the bottom of the standpipe and extending into the water receptacle.

3. In combination with a coke oven having an opening through its top for the escape of gas therefrom, a water receptacle supported on the top of the oven structure and surrounding said opening, a fixed standpipe supported above said opening having an an-

nular outwardly extending flange at its base and a vertically movable standpipe extension having an inwardly extending flange at its top adapted to rest on the flange at the base of the standpipe and support the extension with its lower edge in the water receptacle.

4. In combination with a coke oven having an opening through its top for the escape of gas therefrom, a sheet metal water receptacle resting on the top of the oven structure formed with a tubular passage through the receptacle registering with the opening in the oven and a standpipe supported above the opening and extending into the water receptacle to a point below the water level therein.

5. In combination with a coke oven having an opening through its top for the escape of gas therefrom, a sheet metal water receptacle resting on the top of the oven structure formed with a tubular passage through the receptacle registering with the opening in the oven, a standpipe supported above the opening and a vertically movable sheet metal standpipe extension adapted to be supported on the bottom of the standpipe and to extend into the water receptacle.

6. Means for cleaning an oven conduit comprising an annular steam generator at the base of the oven conduit providing a passage therethrough for the exhaust of an oven into the conduit, said steam generator being in the form of a receptacle containing water and into which water the lower end of the conduit extends to establish communication between said steam generator and said oven conduit.

7. Means for cleaning an oven conduit comprising an annular steam generator at the base of the oven conduit providing a passage therethrough for the exhaust of an oven into the conduit, and means movably suspended from the oven conduit with its lower end shielded by the steam generator and establishing communication between said steam generator and said oven conduit.
